VAPOR ELECTRIC DEVICE

Paul A. Halpine, Pittsburgh, Pa., assignor to
Westinghouse Electric Corporation, East Pitts-
burgh, Pa., a corporation of Pennsylvania

Application July 31, 1947, Serial No. 764,995

7 Claims. (Cl. 250—27.5)

1

My invention relates to vapor electric devices and particularly to a construction of such a device for withstanding shock or vibration.

Heretofore in the application of vapor electric devices, it has been customary to mount the devices on relatively stable mountings. However, when utilizing such devices on moving vehicles, such as boats or locomotives, the devices become subject to varying and excessive shock and vibration. Vibration has several effects detrimental to the operation of the devices. First, it is able to displace the liquid cathode material so as to inhibit normal operation of the device. Further, the vibration is liable to break the seals which maintain the vacuum tight insulative relation between certain elements of the device. I have found that these deleterious effects can be materially offset by providing a cathode pool having transverse baffles which substantially inhibit movement of the cathode material.

I have found further that the seals may be materially reenforced by eliminating a major portion of the usual vitreous seal and substituting therefor a metallic element and making the seals in the form of substantially enclosed annular bead-like members in which the strains are substantially absorbed by the metal portions of the seal. In order to prevent flashover of the exterior of the seal, an insulating material can be applied over all or a portion of the metal parts comprising the major portion of the seal.

It is accordingly an object of my invention to provide a stabilized electric valve.

It is a further object of my invention to provide an electric valve capable of extensive operation under shock conditions.

It is a further object of my invention to provide an improved seal for a vapor electric device.

Other objects and advantages of my invention will be apparent from the following detailed description taken in conjunction with the accompanying drawing, in which the figure is an elevation, partially in section, of a vapor electric device according to my invention.

In the exemplary embodiment of my invention, the vapor electric device comprises a metallic envelope 1 in which are placed a plurality of co-operating electrodes, such as an anode 2 which may be constructed of any suitable material, preferably graphite, a pool-type cathode 3 placed on the bottom of the container 1, a make-alive electrode 4 for initiating cathode spots on the cathode material, the make-alive electrode 4 being provided with an insulated lead-in bushing 5, preferably extending through the bottom header 6 of the envelope 1.

Also, it is customary to provide a plurality of shields 7 and 8 between the anode 2 and cathode 3, which may or may not have control poten-

tials applied thereto dependent upon the operating conditions in the tube.

The anode 2 is supported by an anode stem 10 which extends through an opening 11 in the envelope 1 and is sealed in an insulating vacuum-type relation by means of my improved anode seal assembly.

Preferably, my improved seal provides a substantially upstanding collar-like element 12 attached to the envelope 1, usually by welding, and surrounding the opening 11 through which the anode stem 10 extends, and attached to the anode stem 10 is a cap 13 of similar material providing downwardly extending edges 14 which are preferably axially aligned with the upstanding edges of the collar 12.

Usually, in order to provide sufficient voltage gradient, it is necessary to apply one or more intermediate body sections 15 of metal and to supply glass seals 15—16 between the various sections of the assembly. In order to make these seals 15—16 substantially shockproof, I provide at least one of each of the meeting edges with a U-shaped contour 18 and assemble the meeting sections in spaced telescoping relation with the U-shaped portion 18 extending over the edge of the meeting section. While either one of the sections 12, 13, 14 may obviously be provided with the U-shaped edges 18, I have found it most convenient to provide the U-shaped edges 18 in the intermediate body portion 14.

While it is possible to use a single tubular body element 14 and split the edge and spin it out into a U-shaped portion, I have found it more convenient to provide two spinnings 19 and 20 which have a push or press fit with each other, and then welding or brazing these portions together to provide a substantially integral body portion 14, the opposite ends of which are provided with U-shaped edges 18 for telescopic relation with the upstanding collar 12 and the dependent cap 13.

To seal the metal portions together substantially bead-like portions 15—16 of vitreous material is applied to the annular U-shaped member 18, and by means of heat is sealed to the edges of the U-shaped member 18, and to the telescoping edge of the abutting element. This annular bead 15 is of such proportions as to completely embed not only the telescoped single edge but the upstanding U-shaped edges 18 so that no sharp edge is exposed beyond the insulating material.

Where the voltage gradient can be met thereby, only one of the bead-like seals 15—16 may be necessary, but usually two or more such seals 15—16 are found to be desirable. Since the bead-like seals 15—16 produce a relatively short creepage distance, a high voltage might break down over the outside of the assembly. Therefore, I provide at least a portion of the metallic elements

with a coating of insulating material 25. I have found that this material may conveniently be glass which is sprayed on in a relatively thin layer and then fused in a furnace to provide an insulating coating 25 extending over the surface of the metallic element. While, of course, this insulating coating may be applied to all or any portion of the metallic elements 12-13-14 of the seal, I have found it most convenient to apply the insulating material to the entire exterior of the metallic body portion 14. If desired, of course, the insulating coating 25 can be applied also to the inner portion of the seal, but usually such extended surfaces are not necessary in the interior of vacuum apparatus.

The bead-like annular seals 15-16 are substantially enclosed in the U-shaped portion 18 so that vibration does not tend to break the vitreous material but is substantially absorbed by the more resilient metal.

To prevent the vibration from displacing the cathode mercury 3 out of contact with the ignitor 4, a plurality of surge suppressors are placed in the cathode container 29. Preferably, the surge compressors take the form of rigid plates or baffles 30. The plates 30 are of less width than the container 29 so as to provide side passages 31 to permit limited movement of the mercury. The plates 30 are secured in spaced criss-crossed relation to substantially inhibit sudden motion of the mercury in response to shock or vibration.

For purposes of illustration, I have shown and described a specific embodiment of my invention. It will be apparent that changes and modifications can be made therein without departing from the true spirit of my invention or the scope of the appended claims.

I claim as my invention:

1. A shock-resistant vapor electric device comprising a metallic envelope, a plurality of cooperating electrodes, one of which is an anode, said envelope having an opening therein, an anode stem attached to said anode and extending through said opening, a sealing structure between said envelope and said anode stem including a sealing member secured to the envelope about the opening, a second sealing member secured to the anode stem, one of said sealing members having a U-shaped edge, said sealing members being assembled in spaced telescoped relation, a bead of vitreous material filling said U-shaped edge and embedding the edges of both members, and a coating of insulating material on a portion of said sealing members.

2. A shock-resistant vapor electric device comprising a metallic envelope, a plurality of cooperating electrodes, one of which is an anode, said envelope having an opening therein, an anode stem attached to said anode and extending through said opening, a sealing structure between said envelope and said anode stem including a sealing member secured to the envelope about the opening, a second sealing member secured to the anode stem, one of said sealing members having a U-shaped edge, said sealing members being assembled in spaced telescoped relation, a bead of vitreous material filling said U-shaped edge and embedding the edges of both members, and a coating of insulating material on a portion of said sealing members, a pool of liquid cathode material in said envelope and a plurality of superposed spaced apart baffles for restraining movement of said cathode material.

3. In a lead-in assembly for a vapor electric device having a metallic envelope comprising a metal collar for attachment to the envelope, a metallic cap-like member having an upstanding edge, an intermediate cylindrical member, said collar, cylindrical member and the upstanding edge of said cap being of substantially the same cross sectional dimensions and assembled in spaced longitudinal relation, one of the adjacent edges being U-shaped and receiving the other in spaced telescoped manner, a bead of vitreous material filling said U-shaped portion and sealed to the edges of both sections, and a layer of insulating material extending over the outer surface of at least a portion of said assembly.

4. An insulating vacuum proof seal for an electric discharge device comprising substantially cylindrical terminal portions, a substantially cylindrical body portion, one of said portions having a U-shaped end and extending around the end of the adjacent portion, a bead of vitreous material filling said U-shaped end and wetted thereto and to the end extending therein and a layer of vitreous material covering said body portion.

5. An anode seal assembly for an electric discharge device comprising a tubular section of metal for attachment to a container, a substantially cylindrical metallic body portion, a metallic cup-like terminal portion, all of said metallic portions being spaced from each other, a vitreous bead sealing the adjacent edges together and a layer of vitreous material covering a part of said metallic portions.

35. 6. A vibration resistant vapor-electric valve comprising a metallic container, a plurality of cooperating electrodes in said container, one of said electrodes being an anode, said container having an opening in the wall thereof, an anode

40 stem attached to said anode and extending through said opening, an upstanding metal collar surrounding said opening and attached to said container, a member attached to said anode stem and having edges extending toward said collar, a tubular body portion, between said collar and said member, said collar, said body portion and said member being in spaced axial alignment, a bead of vitreous material sealing said member to said body portion, a second bead of vitreous material sealing said collar to said body portion and a layer of insulating material covering the outer surface of said body portion.

7. A vibration resistant vapor-electric valve comprising a metallic container, a plurality of cooperating electrodes in said container, one of said electrodes being an anode, said container having an opening in the wall thereof, an anode stem attached to said anode and extending through said opening, an upstanding metal collar surrounding said opening and attached to said container, a member attached to said anode stem and having edges extending toward said collar, a tubular body portion, between said collar and said member, said collar, said body portion and said member being in spaced axial alignment, a bead of vitreous material sealing said member to said body portion, a second bead of vitreous material sealing said collar to said body portion and a layer of insulating material covering the outer surface of said body portion, a pool of liquid cathode material in said container and a plurality of superposed spaced apart surge suppressors in said pool.
